UNITED STATES PATENT OFFICE.

GEORGE HENRY WHEARY, OF RACINE, WISCONSIN.

TRUNK-TRIMMING.

1,265,847.

Specification of Letters Patent. Patented May 14, 1918.

Application filed February 17, 1915. Serial No. 8,881.

To all whom it may concern:

Be it known that I, GEORGE HENRY WHEARY, a citizen of the United States, and resident of Racine, in the county of Racine and State of Wisconsin, have invented new and useful Improvements in Trunk-Trimming, of which the following is a description, reference being had to the accompanying drawings, which are a part of this specification.

This invention relates to improvements in trunk trimmings more particularly adapted for use with wardrobe trunks.

Many trunks of the better class now on the market rest upon one end and are divided vertically, medially into two hinged together sections, the upper end of one of said sections being open at its upper end and is provided with a hinged top cover section.

The trunk sections and top have heretofore been connected together by separate top and side locking trimmings. As thus secured the connections in many ways lack the strength and rigidity desired in the manufacture of trunks.

It is one of the objects of the present invention to overcome the before mentioned objectionable features by combining the trimmings adjacent the top and the corner joint of the sections and the cover into one trimming and thereby provided a trimming which possesses greater strength and rigidity than the same parts used independently.

A further object of the invention is to provide a trunk trimming which is adapted to bind and lock the adjacent sections and top cover of a trunk of the before mentioned type in order to resist torsional strains or working of the parts with relation to each other, and to bind the parts when in closed position, into a rigid structure.

A further object of the invention is to provide a three part trunk trimming which is so constructed as to automatically lock the top cover and trunk sections together when said parts are swung to closed position so that the top cover cannot be opened until the sections have been swung to open position.

A further object of the invention is to provide a trunk trimming which is of very simple construction, is strong and durable,

and which may be manufactured at a minimum cost.

With the above and other objects in view, the invention consists of the improved trunk trimming, and its parts and combinations as set forth in the claims, and all equivalents thereof.

In the accompanying drawing in which the same reference characters indicate the same parts in all of the views:

Fig. 1 is a front view of a wardrobe trunk provided with the improved trimming, the trunk being indicated by dotted lines;

Fig. 2 is a side view of the improved fixture, the parts being shown in separate positions and also with parts broken away;

Fig. 3 is a top view of the trimming, parts broken away; and

Fig. 4 is an edge view of the fixture.

Referring to the drawing the numeral 5 indicates a wardrobe trunk divided medially, vertically to form a body section 6 and 7 a wardrobe section 7 which are hinged together along their rear vertical edges. The wardrobe section has an open upper end closed by a top or cover 8 which is hinged to the upper rear edge of the wardrobe section and the improved fixture 9 is mounted on the top and front side of the trunk at the junction of the two sections and the top cover. The improved fixture 9 is in three parts and comprises the main body portion 80

10, the wardrobe section member 11 and the top cover member 12 which are mounted respectively on the body section, the wardrobe section and the wardrobe top cover of said trunk. The fixture is stamped from heavy sheet metal and when assembled is of approximately elongated rectangular shape and is bent transversely medially of its length into L-shape to form the top portion 13 and the side portion 14. While the transverse bend is of rounded form as indicated by the numeral 15 to conform to the rounded edge portion of the trunk, it is to be understood that the corners may be formed with a right angled bend if desired.

The rectangular piece of material is divided medially vertically to form the body member 10 and the other half portion is divided horizontally near its lower end por-

tion to form the top cover member 12 and the wardrobe section member 11 before described.

The parts of the trimming are secured to 5 the respective parts of the trunk by nails or other fastening means 16 which pass through openings 9' in the trimming in the ordinary manner.

The top or horizontally extending portion 10 of the rectangular member has an upwardly embossed circular rib 17 of semi-circular form in cross section, one half portion of the rib being formed on each upper section and the ends of the half rib on the body section 15 portion are provided with projecting tongues 18 which enter the recesses 19 formed by the ends of the other half rib of the top cover member 12.

The side or vertically extending portion 20 of the rectangular piece of material also has an outwardly embossed circular rib 20 of half circular form in cross section which includes the body section, the wardrobe section and the top cover member of the trimming. The center of this side circular rib is coincident with the corner 21 of the junction of the three portions of the trunk so that one half of the rib is formed on the body portion and the other two members are each provided with one quarter portion of the rib. The end portions of the side half rib are provided with projecting tongues 22 which enter the recesses 23 and 24 formed by the rib portions of the other two members, 35 and the lower end of the rib of the top cover member is also provided with a projecting rib 25 which enters the recess 26 formed by the upper end portion of the rib part of the wardrobe section of the trunk.

40 All of the projecting tongues are slightly offset inwardly at their points of junction with embossed portions of the trimmings as indicated by the numeral 27 so that the parts of the trimmings will lie flush with one another when swung into edgewise engagement with each other.

By thus combining the upper trimming with the front side trimming of the upper portion of the trunk a much stronger trimming is provided which more securely binds the three sections of the trunk together, and by thus combining the parts the fixture is less expensive to manufacture and to attach to a trunk.

55 From the foregoing description it will be seen that the trunk trimming is of very simple construction and is well adapted for the purpose described.

What I claim as my invention is:

60 1. A trunk trimming consisting of a member formed of three independently movable parts having a tongue and recess engagement with each other when in closed position for locking two of the parts together

while the said two parts are engaged by a 65 third part, two of said parts being L-shaped to engage angular portions of a trunk.

2. A trunk trimming, comprising an angular body section member, an angular top 70 cover member, and a third member, all of said members having a tongue and recess engagement with each other, the third member and the top cover member being locked together when engaged by the body section 75 member.

3. A trunk trimming, comprising an angular body section member having tongues projecting from one of its edge portions, an angular top cover member having an 80 edgewise engagement with the body member and provided with recessed portions into which some of the tongues of the body member extend, said top cover member also provided with an endwise projecting tongue, 85 and a third member having an edgewise engagement with the other two members and provided with recessed portions which are entered by the tongue of the top cover member and one of the tongues of the body 90 member.

4. A trunk trimming, comprising an angular body section member having tongues projecting from one of its side portions, 95 said tongues projecting from the ends of part circular ribs embossed outwardly from said body member, an angular top member having an edgewise engagement with the body member and provided with part circular ribs embossed outwardly therefrom to form 100 recesses into which some of the tongues of the body member extend, one of the ribs of the top member having a tongue projecting therefrom, and a third member having an edgewise engagement with the other two 105 members and provided with a part circular rib to form recesses which are entered by one of the tongues of the body member and the tongue of the top cover member, said top cover member and the third member being locked together when engaged by the 110 body member.

5. A trunk trimming, comprising an angular body section member having tongues projecting from one of its side portions, 115 said tongues projecting from the ends of part circular ribs embossed outwardly from said body member, an angular top member having an edgewise engagement with the body member and provided with part circular ribs embossed outwardly therefrom to form recesses into which some of the tongues of the body member extend, one 120 of the ribs of the top member having a tongue projecting therefrom, and a third member having an edgewise engagement with the other two members and provided with a part circular rib to form 125 recesses which are entered by one of the tongues of the body member and the tongue of the top cover member, said top cover member and the third member being locked together when engaged by the body member.

cesses which are entered by one of the tongues of the body member and the tongue of the top cover member, all of said tongues being offset inwardly from the ribs to form flush joints between the parts, said cover member and the third member being locked together when engaged by the body member.

In testimony whereof, I affix my signature in presence of two witnesses.

GEORGE HENRY WHEARY.
